ELEVATOR DOOR OPERATING SYSTEM

Edgar M. Bouton, Nutley, N. J., assignor to Westinghouse Electric Elevator Company, Jersey City, N. J., a corporation of Illinois

Application June 22, 1939, Serial No. 280,470

9 Claims. (Cl. 187—57)

My invention relates to elevator systems, and more particularly to the door locking devices for interlocking the hatchway doors thereof with the control system for the cars.

In many elevator installations in which the hoisting motor is operated by means of a motor generator set, it is usual to provide push buttons in each car for shutting down the motor generator set associated with the car. When the doors are operated by toggle lever arms, they are locked shut when closed, not only by the straight-line action of the toggle levers, but also by an interlocking door lock. In many of these installations the hatchway door locking latches are released by electro-magnetic devices into locking position when the car makes a stop at a floor.

Usually a service key is provided for moving the toggle levers out of the straight-arm position and an emergency key is provided for unlocking the locking latches on the hatchway doors. Heretofore in such installations, it has been impossible, with the car at the parking floor, to shut down the motor generator set from within the car, leave the car and close the doors, without making it necessary to use the emergency key to unlock the doors, unless a button is installed in the corridor at the parking floor to start the motor generator set and thus cause the locking latch to be released from its locking position. The installation of such a starting button involves expense in running an alternating current riser from that floor to the penthouse and other difficulties.

Hence, it is an object of my invention to provide an elevator door operating system for an elevator having a motor generator set, in which the car may be parked at a parking floor, the motor generator set shut down by operating a button in the car and then the hatchway doors closed, without causing the lock thereon to be locked in such manner as to require both a service key and an emergency key to be used to regain admittance to the car.

Another object is to provide an elevator door operating system in which it will not be necessary to install a motor generator set starting button in any corridor leading to the car.

A further object is to provide a simple and inexpensive but accurate auxiliary means for preventing the locking of the interlock on the hatchway doors at a parking floor when the car is stopped at that floor, the motor generator set shut down, and the hatchway door closed.

A still further object is to facilitate the rapid opening of doors to start up a car and insure the opening of the door safety circuit, by opening

the doors before the M. G. set is started, through means located within the car, operable by an attendant.

For a better understanding of the invention, reference may be had to the accompanying drawings, in which:

Figure 1 is a diagrammatic representation of an elevator system with which my invention may be used.

Fig. 2 is a view in front elevation of a corridor door for the car shown in Fig. 1 with a door operating mechanism and an interlock therefor.

Fig. 3 is a view in side elevation of the interior construction of the door interlock embodied in Fig. 2 with the locking latch in locking position.

Fig. 4 is a bottom plan view of the interlock shown in Fig. 3.

Fig. 5 is a view in side elevation of the interlock corresponding to Fig. 3 but with one of the switches eliminated for the sake of simplicity and 20 with the locking latch held in its open position by an auxiliary device in accordance with my invention.

Fig. 6 is a view taken along the line VI—VI of Fig. 5.

Fig. 7 is a diagram in the straight-line style of the control system for operating the doors of the elevator system shown in Fig. 1, and

Fig. 7A is a key representation of the relays embodied in Fig. 7.

The relays in Fig. 7A are illustrated with their coils and contact members disposed in horizontal alignment with their positions in the straight-line circuits of Fig. 7, so that their locations therein may be readily determined.

The following relays are used in the circuits of Fig. 7.

OR=door opening relay.

CR=door closing relay.

1N=lock-releasing coil at first floor.

40

2N=lock-releasing coil at second floor.

3N=lock-releasing coil at third floor.

T=inductor relay coil on car.

K=interlocking relay.

M=car running relay.

45

S=motor-generator starting relay.

L=auxiliary latch coil.

Referring more particularly to Fig. 1 of the drawings, I have illustrated an elevator system as comprising a car 10 suitably suspended by a cable 11 passing over a hoisting drum 12 to a suitable counterweight 13. The hoisting drum is directly coupled to a hoisting motor 14 by a shaft 15. A variable voltage system of control, such as a Ward-Leonard system, is provided for operating

50

55

the hoisting motor 14 wherein the motor is operated by a suitable generator 17 mounted upon a shaft 18 driven by a motor 19. The motor 19 also drives an exciter 20 for supplying energy to the field windings 21 of the hoisting motor and to the control circuit represented by the conductors L+! and L-!. The driving motor is illustrated as a three-phase alternating current motor which may be connected to any suitable source of power by means of the supply conductors I, II and III.

A motor generator starting relay S is provided for starting and stopping the motor generator set. A "start" button 32 and a "stop" button 32A are mounted in the car for controlling the relay S so that the attendant may start or shut down the motor generator set from within the car.

The car is provided with a door or gate 23 and each floor landing is provided with a hatchway door 24. A motor C having an armature CA and a field winding CF is mounted on top of the car for operating the car gate.

As illustrated in Fig. 2, the hatchway door 24 for the first floor comprises a pair of horizontally sliding door panels 25 and 26 suspended from an overhead track rail 28 by a plurality of hangers 28 so that they may be readily moved to the right along the track rail in opening the door. A pair of toggle levers 30 and 31 are pivotally mounted on the door panels for use in opening and closing them. A hand grip 32 is disposed on the side of the arm 31 to permit the arms to be operated manually when desired. The right-hand end of the arm 31 is pivotally attached to one end of an operating arm 33, the other end of which is pivotally attached to a frame 34 mounted on the side wall 35 of the hatchway.

The door may be operated by a power device represented by a motor 1H, having its lower end pivotally attached to a bracket 37 on the lower end of the bracket 34. The motor is disposed to actuate a shaft or arm 39 attached to a bell lever 40 which, in turn, is secured by a link 41 to the operating arm 33. When the motor is operated in one direction the shaft 39 will move upwardly thereby operating the bell crank lever 40, the link 41 and the arm 33 to effect an opening of the door panels 25 and 26. When the motor is reversed, the shaft 39 is pulled downwardly to cause the arm 33 to effect the closing of the door panels.

Although a motor is provided for each corridor door and the car gate, it is to be understood that the motors and their operating levers specifically are so designed that the doors and the gate may be moved by hand at any time, if unlocked.

Each hatchway door is operated by a similar motor, those for the second and third floor being indicated in Fig. 7 by the armatures 2-HA and 3-HA respectively.

The hatchway door motors and the car door motor are preferably of series wound direct current type. Their armatures and field windings are connected in series, with the armatures in parallel with each other and with the field windings in parallel with each other. Each hatchway landing is provided with a switch disposed to be operated by an inductor relay T on the car when it stops at that landing, for connecting the field winding and the armature winding of the door motor at that landing to the door operating circuit.

The floor switch responsive to the inductor relay for the first floor is designated as 1T, that

for the second floor as 2T and that for the third floor as 3T. The inductor relay is connected to be controlled by some means associated with the stopping of the car, such as a speed governor G. While the car is operating, the governor prevents energization of the inductor relay. When the car comes to a stop at a floor, the governor closes its contact members to energize the inductor relay for operating the inductor switch at that floor to prepare the door operating motor 10 thereat for operation.

The circuit for the car motor and the hatchway motors in Fig. 7 does not illustrate the resistors and various detailed refinements usually included in such circuits but further information regarding such details may be secured from the Ellis and McCormick Patent No. 1,934,590, issued November 7, 1933, if desired.

A door opening relay OR and a door closing relay CR are provided for controlling the operation of the gate and door operating circuit. These relays may be energized by a car switch (not shown) disposed in the car or they may be controlled by electrical connections to the car control system which will cause the car door and the hatchway door to open when the car makes a stop at a floor and to automatically close when the car prepares to leave the floor.

An interlocking lock for each hatchway door is provided in order that they may be interlocked with the car control system to prevent the doors from being opened while the car is not making a stop thereat and also in order to prevent the car from being operated while any door remains unlocked.

The interlocking lock for the hatchway door at the first floor is indicated by the numeral 45 and is mounted on the bracket 34 by means of a plurality of bolts 46 (Fig. 3).

The lock comprises a cast metal frame or casing 50, having an upper slot 51 and a lower slot 52 in which locking bar 47 slides up and down when the motor 1H opens and closes the door. A plate 53 is secured to the frame 50 in front of the slots to maintain the bar 47 in its vertical position therein. A pair of side plates 54 and 54a are also provided to cover the working parts. The upper end of the bar 47 is pivotally connected to the end 48 of the door operating link 41 so that operation of the door to open position will pull the bar upwardly and closing the door will move the bar downwardly. The inner face of the portion of the locking bar within the casing is provided with a pair of locking notches 55 and 56 disposed to receive a locking latch 57 while the car is not making a stop at that floor. The latch is formed with a hub 58 which is pivotally mounted in the casing 50 on a cross pin 59. The hub 58 of the locking member is also provided with a weighted arm 60 which biases the latch 57 to its locking position.

An electromagnetic coil 1N is mounted directly above the weighted arm 60 by means of a bolt 62 screwed into a cross-section 63 of the lock frame. When the coil is energized, it will attract the arm 60 and thereby move the latch 57 out of its locking position in the notch 55 or 56. When the coil is deenergized, the force of gravity will cause the arm 60 to move the latch into its locking position when the door is closed. The coil 1N is electrically connected by conductors 64 attached to a terminal board 65 mounted in the upper portion of the casing 50 and leading through a conduit opening 66 in the top of the frame to the control circuits for the car. The

coil 1N is connected for operation by the inductor relay T on the car. When the car stops at a floor, the relay T is energized to close the circuit for energizing the coil 1N.

5 In addition to locking the door when it is closed and placing the car in condition for operation, the locking latch also controls a pair of contact members 1N1 to keep the car from being operated until the door is locked. When the latch is in 10 locking position, these contact members are closed to energize an interlocking relay K of the car control system to permit operation of the car. While the locking latch is in its unlocked position, these contact members remain open to prevent 15 operation of the car. One of the contact members is mounted on the outer end of an insulating block 67, the inner end of which is securely fastened to a projecting arm 68 molded on the hub of the locking latch. The other contact 20 member is mounted on an insulating block 69 secured to a bracket 70 mounted in the lower part of the frame 50. The contact members may be connected in the circuit of the relay K through suitable conductors 71 and 72 running out of the 25 casing 50 through a conduit 73.

The locks for the second and third floor doors are provided with operating coils 2N and 3N, locking latches 57-2 and 57-3 and contact members 2N1 and 3N1, respectively, for locking, unlocking and interlocking them with the control circuit of the car. The circuit for the lock operating coils 1N, 2N, and 3N includes contact 30 members U and D of the up direction and the down direction switches (not shown) which prevent energization of the coils to release the locks while the car is in operation.

In elevator systems it is customary to select one floor as the parking floor at which the car may be stationed when resting or out of operation. Usually the first floor is selected as the 40 parking floor and the door at that floor is provided with a service key means to unlock its toggle levers and an emergency key means to unlock its interlocking lock.

45 In the system illustrated, the first floor is selected as the predetermined parking floor. When the door panels are closed, the straight-line position of the toggle levers 30 and 31 will lock the door against an opening movement by anyone in the corridor. In order to break the straight 50 arm locking action of the toggle levers, a keyhole 43 is provided in the panel 26 just above the pivotal joint between the two levers so that a service key 43a may be inserted from the corridor side to break the toggle joint and thus permit 55 the door to be opened from the corridor.

The emergency key means comprises an emergency releasing arm 75 for raising the locking latch 57 out of its locking position when any condition requires the latch to be forcibly released. 60 One end of the releasing arm is fixed on a pin 76 rotatably disposed in the side wall of the casing 50 and its other end is disposed under the arm 60 of the latch, so that anticlockwise rotation of the pin will cause the arm 75 to raise the arm 60 on the latch and thereby lift the latch out of its locking position. The means for rotating the 65 pin comprises an arm 77 having its one end securely fixed to the outer end of the pin and its other end attached to a cable 78 extending upwardly along the side of the casing to an emergency box 79 on the hatchway wall.

The outer face of the emergency box may be provided with a glass cover (not shown) facing into the corridor so that the glass may be broken 70 at any time to permit the use of an emergency

key (not shown) for operating the cable to pull upwardly on the operating lever 77 and thereby cause the pin 76 to raise the emergency lever 75 to move the locking latch out of its locking position. A tension spring 80 having its one end 5 attached to the outer end of the lever 77 and its other end to a screw 81 in the casing is provided for biasing the emergency lever away from the locking latch so that it will not engage the latch except the emergency key is used. Inasmuch as 10 such emergency releasing devices are old and well known in the art, further description thereof will be omitted.

A car running relay M is provided for conditioning the car control system for operation and 15 to indicate that the motor generator set is operating. A "condition-to-run" button R and an emergency stop button E for controlling this relay are mounted in the car to be operated by the 20 car attendant. A pair of field protective relay contact members FP and a pair of counterweight overspeed contact members FC are connected in the circuit of the relay M to prevent its operation under unsafe conditions.

If the operator shuts down the motor generator 25 set, leaves the car and closes the doors, the toggle arms will move into their straight line position and lock the door so that the door cannot be opened without the use of the service key to break the toggle joint. The shutting down of the motor 30 generator set causes the energizing coil in the interlocking lock to be deenergized, thus permitting the locking latch 57 to fall into its locking position. With the car at the floor and with the locking latch in locking position and the 35 toggle arms in locking position, the door cannot be opened unless the motor generator set is started or unless the glass on the emergency box is broken and the emergency lock operated to release the locking latch in addition to using the 40 service key to break the toggle joint of the toggle arms.

Heretofore, in order to avoid the necessity of using both the emergency key and the service key to gain entrance to the car, it has been customary to install a motor generator starting button in the corridor at the parking floor so that the door interlock will be released and the attendant may regain admittance to the car by using only the service key. The installation of 45 a motor generator starting button in the corridor at the parking floor entails the expense and difficulty of running alternating current risers from the parking floor to the penthouse.

In order to avoid this expense and difficulty, 50 I have provided a novel system including an auxiliary latch 83 (Fig. 5) operated by an auxiliary coil L for preventing the locking latch 57 from moving into its locking position when the car is parked at the parking floor, the motor generator 55 set shut down and the door closed.

The auxiliary latch 83 is pivotally mounted by a pin 87 on a bracket 84 secured to the casing plate 53 in position to engage an auxiliary arm 85 molded on the hub of the latch 57 and extending through a slot 86 in the plate 53 when the latch 57 is in its open position. The left hand arm of the auxiliary latch extends horizontally to constitute an armature 88 for the auxiliary coil L. When the auxiliary coil is energized, it 60 attracts the armature 88 and consequently pulls the auxiliary latch 83 away from the latch 57. When the auxiliary coil is deenergized, it releases the armature 88 and the weight of the armature biases the latch 83 to swing in above the arm 65 70 75 85 to prevent the latch 57 from closing. The 78

energization of the coil L is controlled by the motor generator relay S, through the car running relay M, to keep the auxiliary latch out of its lock preventing position while the motor generator set is running.

An assumed operation of the system is as follows. It will be assumed that the motor generator starting relay S, the interlocking relay K, the car running relay M, and the auxiliary latch coil L are energized, that the first floor has been selected as the parking floor and that the car is moving down to the first floor, with the car gate and all the hatchway doors closed and locked.

Assuming that the attendant on the car stops the car at the first or parking floor, then this action causes the governor G to close its contact members G1 to energize the inductor coil relay T on the car. Inasmuch as the car is at the first floor, the coil T operates the plate P1 to close its contact members T1, T2, and T3 for the purpose of operating the door interlock for the first floor and for preparing the hatchway door motor at that floor and the car gate motor for operation. The closing of the contact members T3 energizes the lock releasing coil IN of the door interlock by the circuit L+1, IN, T3, U, D, L-1. The energized coil IN attracts the armature 80 and which moves the latch 57 out of its locking notch 55 in the lock shaft 47. The opening movement of the latch 57 unlocks the door and opens the contact members N1, thereby deenergizing the interlocking relay K which opens its contact members K1 in the control circuit of the car to prevent operation of the car while the door is unlocked.

It will be assumed now that the car attendant or the car control system operates the coil OQ to close its contact members OQ1 for energizing the door and gate opening relay OR by the circuit L+1, M1, OR, OQ1, CR1, OL, L-1. The energized relay OR causes the hatchway door at the first floor and the car gate to open, by opening its contact members OR1 and closing OR2, OR3, OR4 and OR5. The closing of the contact members OR4 and OR5 energizes the motor C for opening the car gate by the circuit L+1, OR4, CF, OR5, r1, CA, L-1. This motor now operates to move the car gate 23 to its open position.

The closing of the contact members OR2 and OR3 energizes the door opening motor 1H by the circuit L+1, OR2, T1, HF, OR3, r1, HA, T2, L-1 and the energized motor moves the door to its open position.

As the door reaches its open position, it opens the limit switch OL in the circuit of the door relay OR, thereby deenergizing that relay and causing it to open its contact members to stop the door motor 1H and the car gate motor C.

The car is now standing at the parking floor with its gate open and the hatchway door at that floor open and anyone may enter or leave the car. However, it will be assumed that no one enters the car and that the car attendant desires to leave the car parked at that floor for a while. Therefore, he presses the button 82A in the car to shut down the motor generator set and then leaves the car.

The pressing of the button 82A deenergizes the relay S which opens its contact members S1—S5 inclusive.

The opening of the contact members S5 deenergizes the car running relay M instantly which in turn opens its contact members M3, thus deenergizing the auxiliary latch coil L. The de-

energized coil L releases the armature 80 and the weight of the armature causes the latch 57 to swing into position above the arm 88 on the locking latch 57 while it is still in its open position to prevent it from moving to its closed position.

The opening of the contact members S1, S3 and S4 opens the circuit for the driving motor 18 causing it to shut down and thereby stop the operation of the generator 17 and the exciter 10 20.

Inasmuch as the supply conductors L+ and L- are provided with energy from the exciter 20, the energization of the lock coil IN on the interlock at the parking floor will fall gradually 15 by reason of the gradual fall of the exciter voltage as the motor generator set slows down to rest. This slow decay in voltage causes the coil IN to hold latch 57 up until after the auxiliary coil L drops the auxiliary latch 83 into position to 20 prevent the latch 57 from moving into its locking position in the notch 56 or the notch 55. Hence it is seen that the predetermined time delay in the deenergization of the coil IN after the deenergization of the coil L gives the auxiliary latch 83 time to fall in above the arm 88 before that arm is released by the coil IN and thereby prevents the latch 57 from falling into its locking position if the door is closed while the motor generator set is shut down with the 30 car at the parking floor.

As the car attendant leaves the car, he closes the hatchway door by hand. The movement of the door to its closed position causes the toggle levers 30 and 31 to fall into their straight-line 35 position and this position of the toggle levers will prevent the hatchway door from being reopened until the motor 1H is energized or the service key is inserted through the service keyhole 43 to unlock the toggle levers.

If it were not for the auxiliary latch 83, the closing of the hatchway door 24 would also cause the latch 57 to fall into the locking notch 55 or 56 and thereby lock the door with the door lock in addition to the locking action of the toggle levers. However, as described above, the auxiliary latch 83 is now disposed above the latch 57 and prevents that latch from locking the door when it reaches its closed position.

It will be assumed now that the car attendant 50 returns. In order to gain admittance to the car he does not need to unlock the door lock (because the latch 57 is not in locking position). All he needs to do to unlock the door is to use his service key to move the toggle levers from their locking 55 position. It will be assumed that he does this and opens the door by hand, enters the car, and presses the MG starting button 82 in the car to start the motor generator set into operation. The closed position of the button 82 energizes 60 the MG starting relay S which closes its contact members S5 to prepare the car running relay circuit for operation. The starting of the MG set causes the exciter to supply energy to the conductors L+1 and L-1 and this energizes 65 the inductor relay T and the interlock relay K. The relay T operates the plate P1 to close its contact members T3 to energize the lock releasing coil IN.

It will be assumed now that the attendant 70 presses the button R in the car to energize the car running relay M in order to condition the car control system for operation. The relay M, energized by the circuit L+1, R, E, FP, Fc, S5, M, L-1, closes its contact members M1, M2, M3 75

and M4. The closed contact members M4 complete a self-holding circuit for the relay M. The closed contact members M3 energize the auxiliary coil L which, in turn, attracts its armature 88, thereby drawing the auxiliary latch 88 out of its lock-preventing position above the latch 51. However, the latch 51 does not fall into its locking position upon the removal of the auxiliary latch 88, because the starting of the motor generator set and the exciter caused energization of the unlocking coil 1N to hold the latch 51 in its unlocking position.

It will be assumed now that the car attendant operates the car control system (not shown) to cause the car to leave the parking floor and in so doing causes the coil CQ to be energized to close its contact members CQ1, thus energizing the door closing relay CR by the circuit L+1, M2, CR, CQ1, OR1, CL, L-1. The energized relay CR opens its contact members CR1 and closes CR2 to CR5, inclusive. The closing of the contact members CR4 and CR5 energizes the car gate motor C to close the car gate and the closing of the contact members CR2 and CR3 energizes the door motor 1H to close the hatchway door. As the door moves to its fully closed position and the up direction switch (not shown) is operated by the car control system for moving the car upwardly, the contact members U open, thereby deenergizing the locking coil 1N which causes the latch 51 to drop into its locking position in the notch 55 as the door reaches its fully closed position. The movement of the latch 51 into the notch 55 closes its interlocking contact members 1N1, thereby energizing the relay K through the circuit L+1, K, 1N1, 2N1, 3N1, L-1. The energized relay K closes its contact members K1, thereby enabling the car to be operated away from the floor inasmuch as the hatchway door is closed and locked by the interlock 48.

It will be apparent from the foregoing description that I have provided a door operating system in which the car attendant may park the car at a predetermined floor and then shut down the motor generator set, leave the car and close the door and later on be able to return and reenter the car with the use of only the service key and without being required to open the emergency lock. It will also be apparent that the emergency lock will cause the door at the parking floor to be locked and interlocked with the car running system at all times when the car is away from that floor and that the auxiliary latch will prevent the interlock at the parking floor from locking the door only when the car is at that floor and the motor generator is shut down.

Although I have illustrated and described only one specific embodiment of my invention, it is to be understood that changes therein and modifications thereof may be made without departing from the spirit and scope of the invention.

I claim as my invention:

1. An elevator door operating system for a car operable by a motor generator set to serve a hatchway door, said system comprising a control device for starting and for shutting down the motor generator set, a lock for the door, and means responsive to operation of the control device to shut down the motor generator set while the car is at said floor for preventing the lock from locking the door when it is closed while the car is at the corresponding floor and the motor generator set is shut down.

2. An elevator door operating system for a car

operable by a motor generator set to serve a hatchway door, said system comprising a locking latch for locking the door when the car is not making a stop thereat, an auxiliary latch for preventing locking operation of the locking latch, control means for conditioning the car for operation, and means responsive to operation of the control means to condition the car for operation for keeping the auxiliary latch out of its preventing position.

3. An elevator door operating system for a car operable by a motor generator set for serving a hatchway door, said system comprising a control device for starting and for shutting down the motor generator set, a device for preparing the car for operation, a locking latch for the door, said latch being biased toward door locking position, an electromagnet for the locking latch, means responsive to operation of the motor generator set and to the stopping of the car at the corresponding floor for energizing the electromagnet to move the latch to its unlocking position, an auxiliary latch biased toward engagement with the locking latch to prevent it from moving from its unlocked position to its locking position, an auxiliary electromagnet for the auxiliary latch, means responsive to operation of the motor generator set and to operation of the car preparing device for energizing the auxiliary electromagnet to move the auxiliary latch out of its preventing position so that the door may be locked while the car is away from the floor.

4. An elevator door operating system for a car operable by a motor generator set for serving a plurality of floors provided with hatchway doors, a lock at one of said doors for locking that door, said lock having a locking latch biased to its door locking position, an auxiliary latch pivotally mounted on the lock in position to normally swing into position to prevent the locking latch from moving from its open position to its locking position, an electromagnet for operating the auxiliary latch to move it out of its lock-preventing position, means for causing the electromagnet to be energized to attract the auxiliary latch while the motor generator set is running and means responsive to shutting down the motor generator set for deenergizing the electromagnet when the motor generator set is shut down to release the auxiliary latch into position to prevent the locking latch from moving into locking position while the motor generator set is shut down.

5. An elevator door operating system for a car operable by a motor generator set for serving a hatchway door, said system comprising a control device for starting and shutting down the motor generator set, a locking latch for locking the door, an electromagnet for the locking latch, means responsive to stopping the car at the corresponding floor for energizing the electromagnet to open the locking latch, an auxiliary latch biased to prevent the locking latch moving from its open position to its closed position, an auxiliary electromagnet for the auxiliary latch, a relay for connecting the auxiliary electromagnet for energization to keep the auxiliary latch out of its lock preventing position while the motor generator set is in operation, and means responsive to operation of the control device to shut down the motor generator set when the car is at the floor for disconnecting the relay and the motor generator set from their sources of energy to cause both electromagnets to be deenergized, said relay being disposed to cause the flux decay therein to proceed more rapidly than the decay of flux in the

- locking electromagnet whereby the auxiliary latch is released a predetermined time ahead of the locking latch to permit the auxiliary latch to prevent movement of the locking latch into locking position when the car is at the floor and the motor generator set is shut down.
6. An elevator door operating system having a car operable by a motor generator set for serving a hatchway door, said system comprising a control device for starting and shutting down the motor generator set, a circuit supplied with energy from the operation of the motor generator set, a locking latch for locking the door, an unlocking electromagnet, means responsive to stopping the car at the corresponding floor for connecting the unlocking electromagnet to the circuit to cause it to be energized to open the locking latch, an auxiliary latch for preventing the locking latch moving from its open position to its closed position, an auxiliary electromagnet, a relay for connecting the auxiliary electromagnet to the circuit for operating it to keep the auxiliary latch out of its lock-preventing position while the motor generator set is in operation, and means responsive to operation of the control device to shut down the motor generator set when the car is at the floor for operating the relay to disconnect the auxiliary relay magnet from said circuit and for disconnecting the motor generator set from its source of energy, the auxiliary electromagnet being deenergized before the deenergization of the locking latch electromagnet whereby the auxiliary latch is moved into its lock preventing position before the locking latch is released by the locking latch electromagnet thus preventing the locking of the door when the car is at the floor and the motor generator set is shut down.
7. An elevator door locking system for a car operable to serve a door at a floor landing, said system comprising a locking latch, an electromagnet for moving the locking latch out of locking position, an auxiliary latch for preventing the locking latch from moving to its locking position, an auxiliary electromagnet for operating the auxiliary latch, means for connecting the electromagnets to sources of energy to cause them to attract the latches, and means for deenergizing first the auxiliary electromagnet and next the locking latch electromagnet when the car is at the floor to cause the latches to operate in a predetermined order.
8. An elevator door lock comprising a casing, a locking latch pivotally supported by the casing in position to normally assume its locking position, an electromagnet mounted above the latch for moving it out of its locking position, a bracket mounted on the face of the casing above the locking latch, an auxiliary latch mounted on the bracket above the locking latch to normally prevent it from moving from its open position to its locking position, and an auxiliary electromagnet mounted on the bracket for operating the auxiliary latch.
9. An elevator door lock comprising a locking latch biased toward locking position, an electromagnet for moving the locking latch out of its locking position, an auxiliary latch biased toward engagement with the locking latch to prevent it from moving from its unlocked position to its locking position, and an auxiliary electromagnet for moving the auxiliary latch away from the locking latch.
